CLAIM

The ornamental design for a sandal, as shown and described.

DESCRIPTION

FIG. 1 is a perspective view of a sandal showing my new design with the front and rear horizontal straps in a closed recessed position;

FIG. 2 is a top plan view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a bottom plan view thereof;

FIG. 8 is a perspective view thereof, illustrated with both of said front and rear horizontal straps in an open raised position;

FIG. 9 is a perspective view thereof, illustrated with said front horizontal strap in a closed recessed position and with said rear horizontal strap in an open raised position; and, FIG. 10 is a perspective view thereof, illustrated with said front horizontal strap in an open raised position and with said rear horizontal strap in a closed recessed position.

The broken lines in the drawings illustrate portions of a sandal that form no part of the claimed design.
